UNITED STATES PATENT OFFICE.

JOSEPH W. COBURN, OF EAST WALPOLE, MASSACHUSETTS.

DOOR-HANGER.

SPECIFICATION forming part of Letters Patent No. 228,607, dated June 8, 1880.

Application filed March 5, 1880. (Model)

To all whom it may concern:

Be it known that I, JOSEPH W. COBURN, of East Walpole, county of Norfolk, State of Massachusetts, have invented an Improvement 5 in Door-Hangers, of which the following description, in connection with the accompanying drawings, is a specification.

This invention relates to sliding-door hangings, and has for its object such a construction thereof, as hereinafter described, as will reduce the friction to the minimum.

In this my invention I have taken an angled plate and provided one face of it with a long slot to receive within it part of the roller, 15 and have provided the said plate with front and rear stops to act against axles of the anti-friction roller and check its movement just before the roller arrives at the ends of the said slot. One part of this angle-plate is provided 20 with screw-holes, by which to attach the plate to the top of the door, and the other part of the plate, or that in which the slot hereinbefore referred to is made, is made to extend horizontally backward over the top of the door, 25 to thereby permit the roller which enters the said slot, and by which the door is rolled, to rest upon a laterally-projecting ledge or shelf connected with, say, a car or other door, the said ledge being shod with the usual angle-iron. This form of hanger can be readily applied to any ordinary freight-cars having the 30 common ledge above the door.

In some other forms of hangers the ledge in which the rollers run has been made double, 35 and been provided with two tracks, and the rollers have been made double, with reduced bearings at their centers, about which was placed a metal strip extended upward from the top of the door between the said tracks. 40 This class of hanger, to be applied to any ordinary freight-car, necessitates more complicated and expensive changes than by my plan.

My invention consists in a hanger composed of an angle-iron, one arm of which is provided 45 with a long slot and roller-stops, and of a roller having journals at each end, the largest part of the said roller entering and moving longitudinally in the said slot as the door with which the said angle-iron is connected is moved 50 longitudinally, the said angle-iron, when at-

tached to the door, bearing, with the whole weight of the door, upon the end journals of the rollers used to support the door.

Figure 1 represents, in side elevation, one set 55 of my hangers supposed to be attached to the top of a car-door; Fig. 2, a vertical section of the same through one of the hangers; Fig. 3, a top view of one of the hangers, and Fig. 4 a rear-side elevation of one of the hangers with the roller on the track. 60

In the drawings, *a* is supposed to represent part of the side of a railroad-car or a building; *b*, the usual ledge, on which is the usual metal track, both commonly found in freight-cars, and *c* the sliding door. 65

As so far described the parts are old, and it is for this old form of cars that I more especially designed my hangers, to thus enable their ready application without changing the car, as by adding an extra track. 70

The angle-plate, composing the chief or largest part of my hanger, has two arms, (as I will call them,) *d e*. Arm *d*, or the vertical arm, when in use, has holes made in it to receive screws *f*, or bolts, by which to attach the 75 hanger to the door. The arm *e*, or horizontal arm, has a long slot, 2, (see Fig. 3,) which receives within it the large central part of the roller *g*, the said slot being substantially as wide as the roller *g* is broad. The end journals, 3, of this roller serve to support the parts 80 of the arm *e* at each side of the slot. The roller *g* rests upon the usual track on the usual ledge *b*. The weight of the door is thrown upon the axles 3, and the rollers support the 85 door on the track.

On the hanger are stops 4 5, that meet the journals 3 and arrest the traverse of the rollers in the slots 2, thereby preventing the large part of the roller *g* from striking the arm at 90 the ends of the said slot.

Referring to Fig. 1, wherein the door is closed, if the door be slid in the direction of the arrow on it the rollers will commence to roll along the track upon the ledge *d*, and at 95 the same time the rollers will gradually fall back along the said slots 2 until their journals 3 are arrested by the stop 5. During this movement of the door the friction between the roller and track and the journals and arm *e* is 100

only that of rolling friction, and the door is moved with but the minimum expenditure of power.

I claim—

5 The herein-described door-hanger, composed of an angle-plate having arms *d* *e*, the latter provided with the long horizontal slot 2 and the stops, and of the roller *g*, having end journals, 3, the large part of the roller being

10 adapted to run in the slot of and to be guided

by the slot of the arm *e* as the roller runs upon the ledge and single track, all substantially as shown and described.

In testimony whereof I have signed my name to this specification in the presence of 15 two subscribing witnesses.

JOSEPH W. COBURN.
